PIPE REAMER

Emory Day Stanley, Cranford, N. J.

Application June 19, 1947, Serial No. 755,567

6 Claims. (Cl. 131—246)

1

The invention relates to means for reaming out the layer of hard ash that forms on the inside of a smoking pipe.

Among the prime objects of the invention are ease and efficiency of operation, combined with cheapness and simplicity of construction. Also it is desirable that the reamer shall be useful for pipe bowls of various sizes, that it shall be self centering and shall avoid the localizing of lateral pressure which may result in the bursting of the pipe bowl.

These and other objects are accomplished by the reamer of this invention. Essentially it has a base member with a rounded bottom which more or less conforms to the bottom of the pipe bowl and serves to center the reamer in the bowl. In addition this rounded bottom has burrs formed on its surface which cooperate in the scraping of the ash, particularly in the bottom of the bowl.

A blade is laid in a slot in the top face of the base member and preferably protrudes at both ends and has a suitable cutter on each protruding end. The blade is removable and different length blades can be used for different size pipes.

As a practical construction, the base member may be a hollow shell or cup of substantially semi-spheroidal shape with the burrs struck out from its wall, being of suitable sheet metal, such as steel. Its top edge will be cut down at opposite points to provide a diametral slot into which the blade will fit, its width and height corresponding to those of the slot.

To secure the blade in the slot during operation, the invention contemplates an axial socket in the bottom of the cup with its top face on the level of the bottom of the slot so that the blade rests upon it. A hole through the blade accommodates a stem which engages in the socket, as by screw threads, and means, such as an integral collar on the stem, bear on the top of the blade and hold it in the slot. The stem is provided with a handle to facilitate turning.

The illustrated embodiment of the invention will now be described, after which the invention will be pointed out in claims.

Fig. 1 is an elevation of a reamer illustrative of the invention and shown on an enlarged scale.

Fig. 2 is a sectional plan of the same in the plane of line 2—2 of Fig. 1.

Fig. 3 is a bottom plan of the same.

Fig. 4 is a sectional elevation on the same scale, showing the reamer with the handle broken away in operative relation to a pipe bowl, the top portion of which is shown, the plane of section

2 of the reamer being on line 4—4 of Fig. 2, looking in the direction of the arrows.

Fig. 5 is a sectional elevation of the reamer elements shown in Fig. 4 but taken on a plane 5 at right angles to Fig. 4, namely, on the plane of line 5—5 of Fig. 3, looking in the direction of the arrows.

In the construction shown, the base member 10 is a hollow cup 1 of steel or other suitable sheet metal and is spherical in shape and comprises substantially half of a complete sphere. Formed on its surface are a series of grating projections, such as burrs 2, which may well be formed by slitting the wall and extruding the metal to the 15 shape of a concavo-convex projection, facing in the direction of turning so that collectively they provide a continuous cutting or abrasive surface when revolved against a softer surface of corresponding concavity.

20 Secured in the bottom of the cup 1, as by welding, is an attaching column or socket member 3 which may be circular in cross section and has an axial recess which is internally screw threaded. On diametrically opposite sections the shell or 25 cup 1 is slotted or cut out, as indicated. The slot thus formed is shown as of the same width as the diameter of the socket member 3 and of a depth to the level of the top face of the socket member.

30 Laid in this slot is a blade 4. In cross section it is of a size to fill the slot. In length it exceeds the diameter of the cup, and hence when centrally disposed in the slot it projects radially at both ends. Being of the width of the slot, 35 it is of the width of the socket member 3 on which it rests. Midway of its ends it is provided with a transverse opening from top to bottom, and when the parts are assembled the blade is so disposed that this opening is in line with the 40 threaded opening in the socket member 3.

A stem 5 enters these aligned openings and secures the blade to the cup. The end of the stem is screw threaded to engage in the socket opening. The section immediately above the 45 screw threads is smooth and of a size and length to fit into the opening in the blade 4. Immediately above this smooth section is an integral collar 6, the plane bottom face of which bears on top of the blade when the stem is screwed into the socket. Thus the blade is clamped to the base.

A suitable handle 7 is secured to the stem 5, being shown as a rod fitting into a transverse hole in the stem.

55 The blade 4 is shown as having a cutter on each

protruding end which may be of any suitable construction. In the illustrated construction, they operate somewhat on the principle of an expansible bit. The end 4a is undercut so as to form a depending sharp cutter point 8 at the extreme end. The end 4b is rounded at the upper part of its thickness and differentially undercut at the lower part to provide a rounded overhanging scraping or cutting edge 9 disposed in an axial plane.

The method of use is illustrated in Fig. 4. As stated, a length of blade will be chosen which is suited to the size of the pipe bowl. The parts are assembled by laying the blade in the slot in the cup with its opening over the socket recess, and the end of the stem is inserted and screwed down as far as the collar 6 permits. Thereafter the reamer body will be turned in a clockwise direction by the turning of the handle.

The reaming has proceeded part way in the situation represented in Fig. 4. A pipe bowl 10 has an internal layer of hardened ash 11. The pipe is grasped in the left hand and the reamer is inserted with the right hand. The rounded bottom automatically centers the reamer. Inward pressure causes the point 8 to make a circular incision at the outer periphery of the area to be cleaned, and the character of the ash is such that this incision will tend to crumble it. The edge 9 follows and cleans off the crumbled particles and assists by cutting and scraping. From time to time, the reamer will need to be removed and the crumbled ash removed. A spoon shaped end 12 of the handle 7 will assist in this operation. When the bottom of the bowl is reached, the burrs on the surface of the cup come into operation and assist in grating away the ash deposit on the rounded portion in the plane of the stem opening. The ash does not ordinarily deposit on the central portion of the bottom of the bowl, hence the burrs will be omitted from that area of the cup surface. Scraping of or injury to the bottom of the bowl is also thus avoided.

It will be noted that the operation produces but a small component of outward pressure, and is therefore unlikely to crack the pipe bowl.

It is obvious that the invention is not limited to the particular details of the construction shown and above described, but that the invention as defined in the following claims may be variously otherwise embodied.

What is claimed is:

1. A smoking pipe reamer comprising a semi-spheroidal base member having a diametral slot in its plane side, a removable blade fitting in the slot and exceeding in length the diameter of the base member and having a cutter on one end, and an axially extending member provided with a handle and securing the blade in the base member with the end of the blade having the cutter protruding from the base member.

2. A smoking pipe reamer comprising a semi-spheroidal base member provided with burrs on its spherical surface and having a diametral slot in its plane side, a removable blade member fitting in the slot and exceeding in length the diameter of the base member and having a cutter on one end, and an axially extending member provided with a handle and securing the blade in the base member with the end of the blade having the cutter protruding from the base member.

3. A smoking pipe reamer comprising a cup member of substantially semi-spheroidal shape having a diametral slot in its annular edge, a threaded socket member axially secured in the bottom of the cup member, a removable blade fitting in the slot and exceeding in length the diameter of the base member and having a cutter on each end and a central opening therethrough, a screw threaded stem extending through said opening and threaded into the socket member and thereby securing the blade centrally disposed on the cup member, and a handle on the stem.

4. A smoking pipe reamer comprising a base member including a shell of substantially semi-spheroidal shape having burrs struck out therefrom and having its annular edge slotted in diametrically opposed portions, and an internally threaded socket member secured axially therein, a removable blade extending across the open side of the base member and fitting in the slot in the edge, the blade exceeding in length the diameter of the shell and having a cutter on a protruding end, a stem engaged in the socket member and engaging and securing the blade in the slot, and a handle on the stem.

5. A smoking pipe reamer comprising a base member including a shell of substantially semi-spheroidal shape having burrs struck out therefrom and having its annular edge slotted in diametrically opposed portions, and an internally threaded socket member secured axially therein, a removable blade extending across the open side of the base member and fitting in the slot in the edge and having an opening therethrough and being of a length to protrude beyond the base member at both ends when the opening is axially over the socket and having a cutter on each of the protruding ends, a stem passing through the opening in the blade and engaged in the socket and having means to bear on the outer side of the blade, and a handle on the stem.

6. A smoking pipe reamer comprising a base member including a shell of substantially semi-spheroidal shape having burrs struck out therefrom and having its annular edge slotted in diametrically opposed portions, and an internally threaded socket member secured axially therein, the socket member having substantially the same width as the slot and having its top face on a level with the bottom of the slot, a blade fitting in the slot and resting on top of the socket member and having an opening therethrough substantially midway of its ends, the length of the blade being such that it protrudes beyond the base member at both ends when the opening is axially over the socket member, a cutter on each end of the blade, a stem passing through the opening and engaged in the socket, means on the stem to hold the blade in the slot when the stem is so engaged, and a handle on the stem.
